COMBINATION LAMP, PICTURE FRAME
AND FLAG HOLDER

Frank L. Poinsett, Box 370, Richwood Road, R.R. 2,
Walton, Ky. 41094

Filed Mar. 24, 1967, Ser. No. 6,719

Term of patent 14 years

(Cl. D48—20)

FIG. 5

FIG. 4

FIG. 1 is a front view of my combination lamp, picture frame and flag holder.

FIG. 2 is an end view of FIG. 1 from the left side thereof.

FIG. 3 is a rear view thereof.

FIG. 4 is a sectional view on line 4—4 of FIG. 1.

FIG. 5 is a sectional view on line 5—5 of FIG. 1, the flag elements and lamp shade not shown for convenience of illustration.

The dominant features of my design reside in the portions shown in full lines.

I claim:

The ornamental design for a combination lamp, picture frame and flag holder, as shown and described.
